UNITED STATES PATENT OFFICE.

RAOUL L. VIORAN, OF CHICAGO, ILLINOIS.

SANITARY CUSPIDOR.

1,103,636.

Specification of Letters Patent. Patented July 14, 1914.

Application filed October 27, 1913. Serial No. 797,371.

To all whom it may concern:

Be it known that I, RAOUL L. VIORAN, a citizen of the United States, residing at Chicago, in the county of Cook and State of Illinois, have invented certain new and useful Improvements in Sanitary Cuspidors, of which the following is a specification.

My invention relates to improvements in cuspidors and has for its object broadly the provision of a sanitary cuspidor which will reduce to a minimum the escape of bacteria from the collected sputum into the atmosphere and which may be readily emptied without danger of the hands of the person performing this operation being contaminated by contact with the receptacle in which the sputum is collected.

An additional object of the invention is to provide a sanitary cuspidor which will automatically and substantially seal itself from the atmosphere after use and which may be easily opened.

A further object of the invention is to provide a sanitary cuspidor in which the sputum and other matter will be received in a receptacle, which may be readily removed and burned or otherwise disposed of in a sanitary manner to prevent spread of bacteria from the sputum and matter removed from the cuspidor.

Another object of the invention is to provide a sanitary cuspidor which, while possessing the foregoing and other advantages, will be pleasing in appearance, durable in operation and which may be cheaply constructed.

Other objects and advantages of the invention will be apparent as it is better understood from the following description when considered in connection with the accompanying drawing illustrating a preferred embodiment thereof.

On the drawing: Figure 1 is a perspective view of a cuspidor embodying my invention placed adjacent and fastened to the wall of a room; Fig. 2 is a transverse sectional view of the same; Fig. 3 is a perspective view of the wire frame forming a part thereof, and Fig. 4 is a similar view of the sputum-collecting receptacle.

On the drawing I have shown a cuspidor embodying my invention constructed to be placed adjacent the side wall of a room, car or other chamber, the device shown and hereinafter described being particularly adapted

for use in Pullman cars and the like where it is desired to place a cuspidor between a pair of seats against a side wall of the car or other compartment.

This embodiment of my invention consists primarily of a holder 11 adapted to rest upon the floor, a readily removable receptacle 12 disposed in the holder, a cover 14 adapted normally to substantially seal the receptacle from the air in the compartment and a device 15 for lifting the cover when it is desired to use the cuspidor. I prefer also to provide means for lifting the receptacle 15 out of the holder 11 which in the present instance comprises a frame 13 of wire or other suitable material.

The holder 11 rests on the floor 16 of the compartment and preferably comprises a substantially semi-circular front wall 17 and a flat back wall 18 fastened at its ends to the ends of the front wall. If desired, a bottom 19 may be provided although it will be apparent as the invention is better understood that an efficient cuspidor may be constructed without providing the receptacle holder with any bottom. The frame 13 fits within the holder 11 and is preferably constructed of wire. In the present instance a top wire 20 is bent into the substantially semi-circular form shown in Fig. 3 and is adapted to fit easily within the holder 11.

A wire 22 is fastened at its ends at 23 to the wire 20 and extends vertically downwardly beneath its connections with the wire 20 to a distance slightly less than the vertical height of the holder and horizontally between the vertically disposed portions thus provided. A wire 24, also fastened at its ends to the wire 20 at 25, is arranged at right angles to the wire 22 and like the wire 22 extends vertically downwardly beneath its connections with the wire 20 and horizontally across the frame beneath the vertically disposed portions. The wire 22 is preferably bent upwardly slightly at 26 where the wires 22 and 24 cross each other, so that both wires may rest on the bottom of the holder or upon the floor of the compartment if the holder is not provided with a bottom. In order that the frame may be readily lifted out of the holder an ear 27 is provided at each side of the frame by bending the wire 20, as shown.

These ears are of sufficient length to extend beyond the outer surface of the holder when

the frame is in place and they rest in slots 28 provided for the purpose in the upper edge of the front wall 17 of the holder.

The receptacle 12 is preferably made of 5 an impervious and non-combustible paper, and is shaped to fit within the frame 13. It consists in the present instance of a flat back wall 29, a substantially semi-cylindrical front wall 30 and a bottom 31, the walls 10 29 and 30 preferably having an appropriate height to dispose their upper edges adjacent or just beneath the upper edges of the walls 17 and 18 of the holder when the parts are positioned, as shown in Fig. 2. The receptacle 15 12 is intended to be thrown away when the cuspidor is cleaned and a new one substituted in its place. If desired, a suitable antiseptic may be deposited in the receptacle when it is placed in the cuspidor al- 20 though it is believed that this is unnecessary. The cuspidor may be emptied without danger of contaminating the hands of the person cleaning the cuspidor by lifting the frame and receptacle out of the cuspidor 25 by the ears 27 and inverting the frame over a collecting bucket into which the receptacle falls and from which the receptacle and the matter collected therein may be burned or otherwise treated to prevent a subsequent 30 escape of bacteria from the matter removed from the cuspidor.

The cover 14 normally closes the cuspidor and fits tightly down against the upper edges of the walls 17 and 18. In order to 35 prevent the cover from noisily closing against these edges after the cuspidor has been opened and to more effectively prevent the escape of bacteria from sputum collected in the receptacle and to more effectively 40 prevent the escape of odor from the matter collected in the cuspidor I provide a gasket 32 secured in a recess 33 in the cover and disposed above the edges of the walls 17 and 18 against which the cover closes. The 45 cover 14 is preferably hinged rearwardly of the wall 18 to rearwardly extending lugs 34 and is preferably weighted at 35 adjacent its forward edge in order that it may move surely and quickly about its pivotal axis to 50 closed position after being raised to open the cuspidor.

In order that a person desiring to use the cuspidor may not have to bend down and lift the cover the device 15 is provided. 55 This device consists in the present instance of a vertically disposed rod 36 provided with a button 37 at its end and a pair of arms 39 preferably made integral with the cover and extending rearwardly of its 60 pivotal connection with the wall 18 of the holder. If desired, a guiding sleeve 38 may be provided to embrace the rod and secure it in place against the wall of the compartment, or other suitable means may be pro- 65 vided to hold the rod in vertical position.

The lower end of the rod 36 is pivotally connected to these arms 39 and downward movement of the rod swings these arms downwardly and lifts the cover. The guide 38 is preferably fastened at its upper end by screws 40, or similar fastening means, to the wall 41 and is free at its lower end so that the bottom end of the rod 36 may move easily with the end of the arms 39 during the operation of the device. The holder 11 is preferably spaced outwardly from the wall 41 to which the guide 38 is secured by the ends 42 of its wall 17, which extend behind the wall 18 for this purpose. If desired, the extremity of these ends may be 70 bent outwardly at right angles as at 43 and secured to the wall by screws 44, or other suitable fastening means, to hold the cuspidor in place. 75

When it is desired to open the cuspidor it is only necessary that the user press down upon the push-button 37, thereby moving the rod 36 vertically downwardly and through the agency of the arms 39 on the cover lifting the cover pivotally to open the cuspidor. After using the cuspidor the release of the button 37 will permit the cover to close under its own weight and substantially seal the interior of the cuspidor from the air of the compartment. As the cuspidor is normally closed the matter collected 90 therein is hidden from sight and the whole effect is pleasing to the eye. There are few parts and all of these are of simple construction so that the cuspidor is durable 95 and economical. 100

The embodiment of the invention shown on the drawing and hereinbefore described is disclosed merely for the purposes of illustration and it will be apparent that various 105 changes may be made in the form, construction and arrangement of the parts, as for instance the cover-lifting device may be disposed within the wall 41 so that only the push button or an equivalent device and the cuspidor itself are visible, without departing from the spirit and scope of the invention or sacrificing any of its material advantages, the form hereinbefore described being merely a preferred embodiment thereof. 115

I claim:

1. A sanitary cuspidor comprising a receptacle holder, a paper receptacle disposed therein, and a rigid wire frame disposed between said receptacle and said holder, said frame comprising a plurality of wire members connected at their bottoms beneath the receptacle and rigidly connected together at their tops. 120

2. A sanitary cuspidor comprising a receptacle holder, a paper receptacle disposed therein, and a rigid wire frame disposed between said paper receptacle and said holder, said frame comprising a plurality of vertically disposed wires rigidly connected at 125 130

their bottoms beneath said receptacle, and means for lifting said frame and receptacle out of the holder comprising members rigidly securing the top of said vertically disposed wires together.

3. A sanitary cuspidor comprising a holder, a receptacle disposed in said holder, a cover pivoted across the rear edge of said holder, means spacing said holder outwardly from the wall of a room, an arm extending rearwardly from the pivotal axis of said cover into the space provided between the wall and said holder, and a rod arranged adjacent said wall connected to said arm and adapted to be pressed downwardly against the force of the weight of said cover to open the cuspidor.

4. A sanitary cuspidor comprising a holder having recesses in its top edge on opposite sides, a paper receptacle disposed in said holder, and a frame comprising a top wire bent to conform to the shape of the holder and provided with outwardly extending loops resting in the recesses of the holder, and cross wires connected at their ends to the top wire and extending downwardly between said holder and said receptacle and across beneath said receptacle.

RAOUL L. VIORAN.
